UNITED STATES PATENT OFFICE

2,542,669

ADJUSTABLE TERMINAL SUPPORTING
INTERCONNECTOR

Howard R. Harrison, Havertown, Pa., assignor to
General Electric Company, a corporation of
New York

Application August 28, 1948, Serial No. 46,603

1 Claim. (Cl. 173—324)

1

The invention relates to electrical connectors, particularly adjustable connectors suitable for use in high voltage power systems as a support for interconnecting bus terminals with misaligned terminals of switches or the like or in another similar service.

One object is to provide an improved form of adjustable posture terminal interconnector that is capable of more universal application in interconnecting various sized bus terminals with the terminals of switches or the like that are spaced from the bus terminals at varying elevations.

Another object is to provide an adjustable posture terminal interconnector that also is capable of mechanically supporting one of the interconnected terminals in variably spaced misalignment with the other, thus eliminating the necessity for an insulating support for the supported terminal.

Another object is to provide limited relative movement between the fixed supporting terminal and the supported terminal while maintaining an effective supporting connection therebetween so as to eliminate difficulties due to expansion and contraction of the bus under different temperature conditions.

Further objects and advantages of the invention will become apparent from the following description of the accompanying drawing in which Fig. 1 is a side view of the improved adjustable posture terminal interconnector applied to interconnect a bus terminal with a relatively fixed grounding switch terminal; Fig. 2 is a top view on an enlarged scale of the improved adjustable posture terminal interconnector shown in Fig. 1 with some of the parts broken away more clearly to reveal the structural details; and Fig. 3 is a side view of the adjustable posture terminal interconnector shown in Fig. 2 indicating by the dotted lines the relatively wide range of adjustment thereof.

As shown in Fig. 1, the improved adjustable posture terminal interconnector indicated generally by the reference character 10 is applied to interconnect the terminal pad 11 that is clamped to the end of the bus 12 with the misaligned but relatively fixed terminal pad 13 of the bus grounding switch 14 which may be of any suitable construction. As shown in the enlarged top view of Fig. 2, the interconnector 10 is provided with a pair of channel-shaped terminal contact members 18 and 19 for attachment respectively to the switch terminal pad 13 and the bus terminal pad 11 by means of suitable holding bolts 20. The contact member 18 is provided with a pair of 58

2

integral spaced-apart arms 21 so as to receive therebetween the flexible current conductor 22 that extends between and electrically interconnects the two terminal contact members 18 and 19. As shown, the opposite ends 23 and 24 of the flexible current conductor 22 are flattened and compacted into a solid mass provided with suitable holes so as to be firmly clamped in good electrical conducting relation between each terminal contact member and the corresponding terminal pad to which it is attached when the bolts 20 are tightened.

The other terminal contact member 19 also is provided with a pair of integral spaced-apart arms 25 so that one end of the H-shaped interconnecting link 26 may be adjustably secured to each of the arms 25 by means of the clamping bolts 27. The link 26 is made in the form of an H so as to be provided with a pair of spaced-apart side arms 28 interconnected by the transverse web 29 that serves to space the side arms 28 apart sufficiently to nest the arms 21 of the terminal contact member 18 therebetween at one end of the link and to nest the arms 25 of the other terminal contact member 19 therebetween at the other end of the link. In order to firmly anchor the side arms 28 of the link 26 to the nested arms 25 of the terminal contact member 19, the toothed spacer washers 31 are interposed therebetween so as to firmly grip the adjacent sides of the nested arms when the bolts 27 are tightened to fix the posture of link 26 and contact member 19.

The opposite end of the link 26 is connected with the nested arms 21 for both rotary and rectilinear sliding movement by means of the pin 33 that extends snugly through holes formed in the ends of the arms 28 and is held in position by the snap rings 34 that fit into suitable grooves formed in the ends of the pin 33. The pin 33 extends through a slot 35 formed in each of the legs 21 of the terminal contact member 18. Thus when the link 26 is firmly secured to the terminal contact member 19 by tightening the bolts 27 to fix the posture thereof, the pin 33 serves to support the end of the bus 12 to which the terminal pad 11 is attached with the pin 33 sliding in slot 35 as the bus 12 expands or contracts under varying temperature conditions.

As indicated in Fig. 3, considerable variation in the elevation of the bus 12 with respect to the switch terminal pad 13 can be accommodated with the improved adjustable posture terminal supporting interconnector of the present invention 59 without damaging the flexible current conductor

22 due to the fact that the link **26** always maintains the conductor **22** slackened as indicated in the drawing and hence prevents undue strains being exerted thereon. Thus the link **26** can be rotated about the pin **33** as an axis into the position indicated by the dash lines and the terminal contact member **19** correspondingly readjusted so as to align with the bus terminal **11** in case the bus should be at a lower level than the switch terminal **13**. If further variation in height is encountered, both the bus terminal pad **11** and the bus terminal contact member **19** may be inverted from their positions in which they are shown in Fig. 3 so as thereby to accommodate further variation in the elevation of bus **12** below the switch terminal pad **13**. This can be accomplished simply by removing the clamping bolts **27** and reassembling the contact terminal pad **19** in its inverted position. For intermediate heights of the bus **12** relative to the switch terminal pad **13**, the end of the bus **12** is shortened to the proper length and the terminal pad **11** clamped thereto by the U bolts **36** so as to mount the terminal interconnector **10** with the pin **33** substantially centrally located in the slots **35**.

Thus it will be seen that the improvements of the present invention enable not only good electrical connection to be established between the interconnected terminals at different levels but also enables the adjustable posture connector to support one of the misaligned terminals in spaced relation with the other while at the same time providing for the necessary relative movement therebetween due to expansion and contraction.

What I claim as new and desire to secure by Letters Patent of the United States is:

An electrical terminal interconnector comprising

ing a pair of terminal contact members, each provided with means for removably clamping the member to a terminal, and each having a pair of arms extending therefrom, a flexible current conductor extending between the members and having the ends thereof formed to be removably clamped with the corresponding member to the corresponding terminal, a link having parallel side arms spaced for nesting the arms of the terminal members between the opposite ends thereof, means for fixedly clamping one end of each of the link arms to a corresponding one of the terminal arms, and means including a slot and a pin sliding therein for connecting the other ends of each of the link arms for both rotary and rectilinear sliding movement with respect to the spaced-apart arms of the other terminal contact member.

HOWARD R. HARRISON.
